ABSTRACT

A vehicle control device includes a plurality of LF transmitters transmitting response request signals that reach an area around a vehicle and an interior of a vehicle chamber, and a UHF receiver receiving a signal transmitted from a portable machine. The portable machine includes an LF receiver receiving the response request signal and a UHF transmitter transmitting a response signal. The LF receiver in the portable machine has a reception region in which the response request signals transmitted from at least two of the LF transmitters are receivable when the portable machine approaches the vehicle. Door locking/unlocking is permitted if the LF receiver in the portable machine receives the response request signals transmitted from at least two of the LF transmitters within a predetermined time period. In contrast, door locking/unlocking is inhibited if the LF receiver receives the response request signal transmitted from one of the LF transmitters.

**CROSS-REFERENCE TO RELATED
APPLICATION**

This application is based on Japanese Patent Application No. 2015-050420 filed with the Japan Patent Office on Mar. 13, 2015, the entire contents of which are incorporated herein by reference.

FIELD

The disclosure relates to a vehicle wireless communication system configured to control a vehicle in accordance with a wireless signal to be transmitted and received between a vehicle control device mounted on the vehicle and a portable machine carried by a user. The disclosure particularly relates to a vehicle security technique.

BACKGROUND

There has been provided a vehicle wireless communication system configured to perform vehicle control, such as door locking/unlocking and engine start, in accordance with a wireless signal to be transmitted and received between a vehicle control device mounted on the vehicle and a portable machine carried by a user. Communication methods between a vehicle control device and a portable machine are roughly divided into three types, namely, a polling method, a passive entry method, and a keyless entry method. According to the polling method, the vehicle control device transmits response request signals at predetermined cycles regardless of the position of the portable machine. According to the passive entry method, the vehicle control device transmits a response request signal to the portable machine when a user approaches or touches a door knob. According to the keyless entry method, the portable machine transmits a signal to the vehicle control device when a user operates the portable machine.

According to the passive entry method, when a user carrying the portable machine approaches or touches a door knob, the vehicle control device transmits a response request signal to the portable machine from each of a plurality of antennas provided to the vehicle. The portable machine receives this response request signal and replies a response signal including an ID code. The vehicle control device collates ID codes upon receipt of this response signal. If matching is successful, the vehicle control device permits door locking/unlocking or engine start. According to the polling method, when a user carrying the portable machine approaches the vehicle, the portable machine receives a response request signal from the vehicle control device and operation similar to the above case is performed subsequently.

There is committed, however, improper communication of cheating as if the portable machine at a far position were located adjacent to the vehicle using a repeater configured to relay a response request signal from the vehicle control device and a response signal from the portable machine. Such improper communication using a repeater is called relay attack. A malicious third party different from an owner of a vehicle may commit a crime such as a theft by unlocking a vehicle door or starting an engine by means of such relay attack.

2

According to JP 2012-144905 A, a single antenna provided to a vehicle transmits a plurality of temporally differentiated measurement signals having different signal strength levels for a security measure against relay attack. If RSSI (received signal strength) values of the measurement signals detected by a portable machine have a difference not more than a threshold, the communication is determined as relay attack and door locking/unlocking and the like are not permitted. The time difference in transmission of the plurality of measurement signals is set to be small such that communication can be determined as relay attack even when the portable machine moves.

According to JP 2010-121297 A, a portable machine detects strength of an LF signal transmitted from a vehicle and the portable machine replies an RF signal including the LF signal strength. After the vehicle detects reception strength of the RF signal, it is determined whether or not the communication is relay attack by comparison between the RF signal strength and the LF signal strength. The portable machine also measures a response time period from reception of the LF signal to transmission of the RF signal and replies the RF signal including the response time period. The vehicle measures a reply time period from transmission of the LF signal to reception of the RF signal, and it is determined whether or not the communication is relay attack by comparison between the response time period and the reply time period.

Furthermore, JP 2006-342545 A discloses providing a vehicle with a plurality of transmission antennas at different positions as well as providing a portable machine with a plurality of reception antennas having different axis directions. The portable machine detects reception strength of each signal from the plurality of transmission antennas at the plurality of reception antennas, and determines whether or not the communication is relay attack by comparing reception strength ratios among the transmitted signals.

The onboard machine and the portable machine have more loads if the processing performed by the onboard machine and the portable machine for security against relay attack is more complicated.

Meanwhile, recent investigation has revealed that a repeater has reception sensitivity much lower than that of a portable machine. When a plurality of onboard transmission antennas each transmit a signal as in JP 2006-342545 A, a repeater may relay a signal transmitted from only one of the transmission antennas. In this case, it is impossible to determine whether or not the communication is relay attack.

SUMMARY

One or more embodiments of the disclosure improve security against relay attack without complication of processing performed by a vehicle control device and a portable machine.

A vehicle wireless communication system according to one or more embodiments of the disclosure is configured to cause a vehicle control device mounted on a vehicle to control the vehicle in accordance with a wireless signal transmitted and received between the vehicle control device and a portable machine carried by a user. The vehicle control device includes: a first transmitter configured to transmit a response request signal to the portable machine; and a first receiver configured to receive a response signal from the portable machine. The portable machine includes: a second receiver configured to receive the response request signal from the vehicle control device; and a second transmitter configured to transmit the response signal to the vehicle.

control device in reply to the response request signal received by the second receiver. The first transmitter includes a plurality of first transmitters to allow the response request signals to reach an area around the vehicle and an interior of a vehicle chamber. The second receiver has a reception region in which the response request signals transmitted from at least two of the first transmitters are receivable by the second receiver when the portable machine approaches the vehicle. Control to the vehicle is permitted if the second receiver receives the response request signals transmitted from at least two of the first transmitters within a predetermined time period, and control to the vehicle is inhibited if the second receiver receives the response request signal transmitted from one of the first transmitters within the predetermined time period.

According to the above configuration, when the portable machine approaches the vehicle, the second receiver in the portable machine receives, within the predetermined time period, the response request signals transmitted from at least two of the first transmitters provided to the vehicle. Control to the vehicle is thus permitted. In contrast, when the portable machine is located far away and a repeater having reception sensitivity much lower than that of the portable machine approaches the vehicle, the second receiver in the portable machine receives, within the predetermined time period via the repeater, the response request signal transmitted from only one of the plurality of first transmitters. Control to the vehicle is thus inhibited. In summary, control to the vehicle is permitted or inhibited depending on whether the portable machine receives, within the predetermined time period, only one or a plurality of response request signals from the first transmitters. It is thus possible to improve security against relay attack using the repeater without complication of the processing performed by the vehicle control device and the portable machine.

According to one or more embodiments of the disclosure, the portable machine optionally causes the second transmitter to transmit the response signal including reception information according to the number of response request signals received by the second receiver within the predetermined time period. In this case, the vehicle control device permits or inhibits control to the vehicle in accordance with the reception information included in the response signal after the first receiver receives the response signal transmitted from the portable machine.

Specifically, the vehicle control device includes a first controller configured to control the first transmitters and the first receiver whereas the portable machine includes a second controller configured to control the second transmitter and the second receiver. The second controller in the portable machine causes the second transmitter to transmit the response signal including the reception information according to the number of response request signals received by the second receiver within the predetermined time period. After the first receiver receives the response signal transmitted from the portable machine, the first controller in the vehicle control device permits control to the vehicle if the reception information included in the response signal indicates that the portable machine receives the response request signals transmitted from at least two of the first transmitters, and inhibits control to the vehicle if the reception information indicates that the portable machine receives the response request signal transmitted from one of the first transmitters.

According to one or more embodiments of the disclosure, optionally, if the second receiver in the portable machine receives the response request signals transmitted from at least two of the first transmitters within the predetermined

time period, the second controller causes the second transmitter to transmit the response signal including reception information according to the number of response request signals, and if the second receiver receives the response request signal transmitted from one of the first transmitters within the predetermined time period, the second controller causes the second transmitter to transmit, instead of the response signal, an inhibiting signal indicative of inhibition of control to the vehicle. The first controller in the vehicle control device permits control to the vehicle in accordance with the response signal if the first receiver receives the response signal transmitted from the portable machine, and inhibits control to the vehicle if the first receiver receives the inhibiting signal transmitted from the portable machine.

According to one or more embodiments of the disclosure, 15 optionally, the portable machine further includes a reception strength detector configured to detect reception strength of the response request signal received by the second receiver, and the reception information relates to reception strength values detected by the reception strength detector, of all the 20 response request signals received by the second receiver within the predetermined time period.

The one or more embodiments of the disclosure achieve improvement in security against relay attack without complication of processing performed by the vehicle control 25 device and the portable machine.

BRIEF DESCRIPTION OF THE DRAWINGS

FIG. 1 is a configuration diagram of a vehicle wireless 30 communication system according to one or more embodiments of the disclosure;

FIG. 2 is a plan view of a vehicle equipped with the vehicle wireless communication system depicted in FIG. 1;

FIGS. 3A and 3B are views indicating signal receivable 35 areas of a portable machine and a repeater;

FIGS. 4A and 4B are exemplary views of locations of the signal receivable areas of the portable machine and the repeater at entry;

FIGS. 5A and 5B are exemplary views of locations of the 40 signal receivable areas of the portable machine and the repeater at engine start;

FIG. 6 is a flowchart of behavior of a vehicle control device according to a first embodiment of the disclosure;

FIG. 7 is a flowchart of behavior of a portable machine 45 according to the first embodiment of the disclosure;

FIG. 8 is a flowchart of behavior of a vehicle control device according to a second embodiment of the disclosure; and

FIG. 9 is a flowchart of behavior of a portable machine 50 according to the second embodiment of the disclosure.

DETAILED DESCRIPTION

Embodiments of the disclosure will be described below 55 with reference to the drawings. In the drawings, the identical or equivalent component is designated by the identical numeral. In embodiments of the disclosure, numerous specific details are set forth in order to provide a more thorough understanding of the invention. However, it will be apparent to one of ordinary skill in the art that the invention may be practiced without these specific details. In other instances, well-known features have not been described in detail to avoid obscuring the invention.

A vehicle wireless communication system 100 according 60 to one or more embodiments of the disclosure will initially be described in terms of its configuration with reference to FIGS. 1 and 2.

FIG. 1 is a configuration diagram of the vehicle wireless communication system 100. FIG. 2 is a view of a vehicle 30 equipped with the vehicle wireless communication system 100.

As depicted in FIG. 1, the vehicle wireless communication system 100 includes a vehicle control device 10 and a portable machine 20. In the vehicle wireless communication system 100, the vehicle control device 10 controls the vehicle 30 (FIG. 2) in accordance with a wireless signal transmitted and received between the vehicle control device 10 and the portable machine 20. In one or more embodiments of the disclosure, control to the vehicle 30 includes locking and unlocking doors of the vehicle 30 serving as an automatic four-wheeled vehicle, and starting an engine thereof. The vehicle 30 is provided with five doors that can be locked and unlocked.

The vehicle wireless communication system 100 includes a keyless entry system of locking and unlocking the doors with switch operation to the portable machine 20 when the portable machine 20 is located adjacent to the vehicle 30, or a passive entry system of locking and unlocking the doors and the like by means of automatic communication with the portable machine 20 when a user approaches or touches a door knob.

FIG. 1 depicts the vehicle control device 10, a power supply 12, a passive request switch 13, an engine switch 14, a door lock device 15, and an engine device 16, which are mounted on the vehicle 30. The portable machine 20 is carried by a user of the vehicle 30.

The vehicle control device 10 includes a controller 1, LF (Low Frequency; long wave) transmitters 2 to 6, and a UHF (Ultra High Frequency; microwave) receiver 7. The controller 1 includes a CPU, a memory, and the like.

The LF transmitters 2 to 6 each include an LF signal transmission circuit and a corresponding one of transmission antennas 2a to 6a. As depicted in FIG. 2, the transmission antennas 2a to 6a of the plurality of (five) LF transmitters 2 to 6 are provided to be dispersed outside and inside a chamber of the vehicle 30.

Specifically, the transmission antenna 2a of the vehicle interior front LF transmitter 2 is disposed at a front portion in the chamber of the vehicle 30. The transmission antenna 3a of the vehicle interior rear LF transmitter 3 is disposed at a rear portion in the chamber of the vehicle 30. The transmission antenna 4a of the vehicle exterior right LF transmitter 4 is disposed adjacent to the exterior of the door at a driver's sheet at the right end of the vehicle 30. The transmission antenna 5a of the vehicle exterior left LF transmitter 5 is disposed adjacent to the exterior of the door at a passenger sheet at the left end of the vehicle 30. The transmission antenna 6a of the vehicle exterior rear LF transmitter 6 is disposed adjacent to the exterior of the rear door of the vehicle 30.

The LF transmitters 2 to 6 each transmit an LF signal in conformity to the polling method to the interior of the vehicle chamber and the exterior of the vehicle chamber around the vehicle 30 in order to communicate with the portable machine 20. The LF signals transmitted from the LF transmitters 2 to 6 include a response request signal for request of a response from the portable machine 20. By providing the vehicle 30 with the plurality of LF transmitters 2 to 6 as describe above, the response request signals reach an area adjacent to the periphery of the vehicle 30 (outside the vehicle chamber) as well as the area inside the vehicle chamber. The LF transmitters 2 to 6 have signal transmission ranges that are overlapped partially. The LF transmitters 2 to

6 exemplify a “first transmitter” according to one or more embodiments of the disclosure.

The UHF receiver 7 includes a UHF signal reception circuit and a reception antenna 7a, and receives a UHF signal transmitted from the portable machine 20. There is provided the only one UHF receiver 7 whereas there is provided the plurality of LF transmitters 2 to 6. The UHF receiver 7 exemplifies a “first receiver” according to one or more embodiments of the disclosure.

10 The controller 1 controls the LF transmitters 2 to 6 and the UHF receiver 7 to transmit and receive signals and information to and from the portable machine 20. The controller 1 exemplifies a “first controller” according to one or more embodiments of the disclosure.

15 The portable machine 20 is a FOB key and includes a controller 21, an LF receiver 22, a UHF transmitter 23, and an operation unit 24. The controller 21 includes a CPU, a memory, and the like.

20 The LF receiver 22 includes an LF signal reception circuit, a reception antenna 22a, and an RSSI detector 22b. The LF receiver 22 receives LF signals transmitted from the LF transmitters 2 to 6 in the vehicle control device 10. The LF signals received by the LF receiver 22 include the response request signal described above. The LF receiver 22 25 exemplifies a “second receiver” according to one or more embodiments of the disclosure.

20 The RSSI detector 22b detects an RSSI value (received signal strength) of the response request signal received by the reception antenna 22a. The RSSI detector 22b exemplifies a “reception strength detector” according to one or more embodiments of the disclosure. The RSSI value exemplifies “reception information” according to one or more embodiments of the disclosure.

35 The UHF transmitter 23 includes a UHF signal transmission circuit and a transmission antenna 23a, and transmits UHF signals to the vehicle control device 10. The UHF signals transmitted from the UHF transmitter 23 include a response signal to be replied to the vehicle control device 10 when the LF receiver 22 receives a response request signal. 40 The UHF transmitter 23 exemplifies a “second transmitter” according to one or more embodiments of the disclosure.

45 The operation unit 24 includes a switch to be operated for locking and unlocking the doors, and the like. The controller 21 controls the LF receiver 22 and the UHF transmitter 23 to transmit and receive signals and information to and from the vehicle control device 10. The controller 21 exemplifies a “second controller” according to one or more embodiments of the disclosure.

50 Connected to the vehicle control device 10 are onboard devices such as the power supply 12, the door lock device 15, and the engine device 16, as well as switches such as the passive request switch 13 and the engine switch 14.

55 The power supply 12 includes a battery configured to supply an electric component of the vehicle 30 with electric power. The passive request switch 13 is disposed adjacent to a door knob on the outer side surface of each of the doors of the vehicle 30. The engine switch 14 is disposed adjacent to the driver's sheet in the chamber of the vehicle 30.

60 The door lock device 15 includes a mechanism configured to lock and unlock each of the doors of the vehicle 30 and a driving circuit for the mechanism. The engine device 16 includes a starter motor configured to drive the engine of the vehicle 30 and a driving circuit for the starter motor.

65 A repeater 50 (FIGS. 3A and 3B) used for relay attack has a function of relaying transmission and reception of signals between the vehicle control device 10 and the portable machine 20 even when the portable machine 20 is located far

away from the vehicle 30. Improper communication is thus made by cheating as if the portable machine 20 at a far position were located adjacent to the vehicle 30.

FIGS. 3A and 3B are views indicating signal receivable areas E1 and E2 of the portable machine 20 and the repeater 50. FIG. 3A indicates a dotted circle corresponding to the signal receivable area E1 in which the LF receiver 22 in the portable machine 20 can receive signals from the LF transmitters 2 to 6 in the vehicle control device 10. FIG. 3B indicates a dotted circle corresponding to the signal receivable area E2 in which the repeater 50 can receive signals from the vehicle control device 10 or the portable machine 20. The signal receivable area E2 of the repeater 50 is much smaller than the signal receivable area E1 of the portable machine 20. The signal receivable area E1 exemplifies a “reception region” according to one or more embodiments of the disclosure.

FIGS. 4A and 4B are exemplary views of locations of the signal receivable areas E1 and E2 of the portable machine 20 and the repeater 50 at entry. FIGS. 5A and 5B are exemplary views of locations of the signal receivable areas E1 and E2 of the portable machine 20 and the repeater 50 at engine start.

As depicted in FIGS. 4A to 5B, assume that the portable machine 20 and the repeater 50 approach the vehicle 30 at equivalent degrees (the portable machine 20 and the repeater 50 are located adjacent to the vehicle outside the vehicle in FIGS. 4A and 4B whereas the portable machine 20 and the repeater 50 are located inside the vehicle in FIGS. 5A and 5B). As depicted in FIGS. 4A and 5A, at least two of the transmission antennas 2a to 6a of the LF transmitters 2 to 6 are located in the signal receivable area E1 of the portable machine 20. In other words, the signal receivable area E1 of the portable machine 20 has a reception region large enough to receive response request signals transmitted from at least two of the LF transmitters 2 to 6.

In contrast, as depicted in FIGS. 4B and 5B, only one of the transmission antennas 2a to 6a of the LF transmitters 2 to 6 is located in the signal receivable area E2 of the repeater 50. In other words, the signal receivable area E2 of the repeater 50 has a reception region large enough to receive a response request signal transmitted from one of the LF transmitters 2 to 6.

The repeater 50 accordingly has reception sensitivity much lower than that of the portable machine 20. The signal receivable areas E1 and E2 specifically exemplify reception sensitivity of the portable machine 20 and the repeater 50.

The vehicle control device 10 and the portable machine 20 become communicable with each other when at least one of the transmission antennas 2a to 6a of the LF transmitters 2 to 6 enters the signal receivable area E1 of the portable machine 20. Specifically, at least one of the LF transmitters 2 to 6 and the UHF receiver 7 in the vehicle control device 10 transmit and receive a response request signal and a response signal to the LF receiver 22 and from the UHF transmitter 23 in the portable machine 20.

The vehicle control device 10 and the portable machine 20 become communicable with each other via the repeater 50 when at least one of the transmission antennas 2a to 6a of the LF transmitters 2 to 6 enters the signal receivable area E2 of the repeater 50. Specifically, at least one of the LF transmitters 2 to 6 and the UHF receiver 7 in the vehicle control device 10 transmit and receive a response request signal and a response signal to the LF receiver 22 and from the UHF transmitter 23 in the portable machine 20 via the repeater 50.

The vehicle control device 10 communicates with the portable machine 20 and collates a preliminarily stored ID code with an ID code applied to the portable machine 20. If these ID codes match, in other words, if matching is successful, predetermined control to the vehicle 30 is permitted.

Specifically, when a user carrying the portable machine 20 operates the passive request switch 13, the controller 1 receives a corresponding operation signal. The controller 1 then communicates with the portable machine 20 using the 10 LF transmitters 2 to 6 and the UHF receiver 7 to collate ID codes. If matching is successful, the controller 1 controls the door lock device 15 to lock or unlock each of the doors of the vehicle 30. (Passive entry method)

When a user carrying the portable machine 20 and 15 approaching the vehicle 30 operates the operation unit 24 in the portable machine 20, the controller 21 causes the UHF transmitter 23 to transmit a signal according to the operation. When the UHF receiver 7 in the vehicle control device 10 receives the signal according to the operation to the operation unit 24, the controller 1 collates ID codes. If matching is successful, the controller 1 controls the door lock device 15 to lock or unlock the doors of the vehicle 30. (Keyless entry method)

When a user carrying the portable machine 20 operates 25 the engine switch 14, the controller 1 receives a corresponding operation signal. The controller 1 then communicates with the portable machine 20 to collate ID codes. If matching is successful, the controller 1 controls the engine device 16 to start or stop the engine of the vehicle 30.

The vehicle control device 10 and the portable machine 20 can communicate with each other in accordance with the 30 polling method instead of the passive entry method (The same applies to a second embodiment to be described later).

The vehicle control device 10 and the portable machine 35 20 according to the first embodiment will be described next in terms of their behavior with reference to FIGS. 4A to 7.

FIG. 6 is a flowchart of behavior of the vehicle control device 10 according to the first embodiment. FIG. 7 is a flowchart of behavior of the portable machine 20 according 40 to the first embodiment.

According to the passive entry method, when the passive 45 request switch 13 is operated, the controller 1 in the vehicle control device 10 causes the LF transmitters 2 to 6 to transmit response request signals in a predetermined order (step S1 in FIG. 6). The LF transmitters 2 to 6 each transmit the response request signal at the timing sequentially delayed at a predetermined interval. According to the polling method, the LF transmitters 2 to 6 transmit response request signals intermittently at predetermined cycles while the 50 vehicle 30 stops, for example.

If the portable machine 20 and the repeater 50 are located 55 away from the vehicle 30 and the transmission antennas 2a to 6a of the LF transmitters 2 to 6 are not located in their signal receivable areas E1 and E2, the LF receiver 22 in the portable machine 20 does not receive the response request signals from the LF transmitters 2 to 6 (NO in step S21 in FIG. 7). Accordingly, with no response signal transmitted from the UHF transmitter 23 in the portable machine 20 and no response signal received by the UHF receiver 7 in the 60 vehicle control device 10 (NO in step S2 in FIG. 6), a predetermined time period T2 elapses (YES in step S3 in FIG. 6). In this case, the controller 1 inhibits locking and unlocking the doors of the vehicle 30 (step S9 in FIG. 6), and also inhibits engine start (step S10 in FIG. 6).

If the portable machine 20 or the repeater 50 approaches 65 the vehicle 30 and at least one of the transmission antennas 2a to 6a of the LF transmitters 2 to 6 enters either one of the

signal receivable areas E1 and E2, the LF receiver 22 in the portable machine 20 receives the response request signal from one of the LF transmitters 2 to 6 (YES in step S21 in FIG. 7). The RSSI detector 22b then detects an RSSI value of the response request signal thus received (step S22 in FIG. 7). The controller 21 associates the RSSI value of the response request signal detected by the RSSI detector 22b with identification information on the corresponding one of the LF transmitters 2 to 6 that are the originators of the response request signal, and stores the same as RSSI information in an internal memory as needed.

If the portable machine 20 approaches the vehicle 30, at least two of the transmission antennas 2a to 6a of the LF transmitters 2 to 6 enter the signal receivable area E1 of the portable machine 20 as depicted in FIG. 4A. Accordingly, the portable machine 20 initially receives the response request signal from one of the LF transmitters 2 to 6 (YES in step S21 in FIG. 7), and then receives the response request signal from another one of the LF transmitters 2 to 6 (YES in step S21 in FIG. 7) before a predetermined time period T1 elapses (NO in step S23 in FIG. 7). The RSSI detector 22b then detects an RSSI value of each of the response request signals thus received (step S22 in FIG. 7).

In contrast, if the portable machine 20 is located away from the vehicle 30 and the repeater 50 approaches the vehicle 30, in other words, if relay attack is committed, only one of the transmission antennas 2a to 6a of the LF transmitters 2 to 6 enters the signal receivable area E2 of the repeater 50 as depicted in FIG. 4B. Accordingly, the predetermined time period T1 elapses after the LF receiver 22 in the portable machine 20 initially receives the response request signal from one of the LF transmitters 2 to 6 via the repeater 50 without receiving any response request signal from another one of the LF transmitters 2 to 6 (YES in step S23 in FIG. 7).

The predetermined time period T1 is set to be short such that, even if the repeater 50 is moved by a person after one of the transmission antennas 2a to 6a of the LF transmitters 2 to 6 enters the signal receivable area E2 of the repeater 50, another one of the transmission antennas 2a to 6a of the LF transmitters 2 to 6 does not enter the signal receivable area E2.

If the predetermined time period T1 elapses after initial reception of the response request signal (YES in step S23 in FIG. 7), the controller 21 generates a response signal including RSSI information indicative of the RSSI values of all the response request signals detected by the RSSI detector 22b and the like and the ID codes preliminarily stored in the internal memory (step S24 in FIG. 7). The controller 21 subsequently causes the UHF transmitter 23 to transmit the response signal thus generated to the vehicle control device 10 (step S25 in FIG. 7). Thereafter, a reception record of the response request signals (e.g. the RSSI information) and measurement information on the predetermined time period T1 are cleared in the portable machine 20.

For example, after the LF transmitters 2 to 6 transmit response request signals (step S1 in FIG. 6) and before the predetermined time period T2 elapses (NO in step S3 in FIG. 6), the UHF receiver 7 in the vehicle control device 10 receives the response signal from the portable machine 20 (YES in step S2 in FIG. 6).

The predetermined time period T2 is set to be equivalent to or slightly longer than an ordinary time period from the time point when the LF transmitters 2 to 6 transmit response request signals to the time point when the UHF receiver 7 receives a response signal from the portable machine 20 in

an exemplary case where a user carrying the portable machine 20 approaches the vehicle 30 for boarding.

Upon receipt of the response signal, the controller 1 refers to the RSSI information included in the response signal and determines whether or not there are at least two RSSI values (step S4 in FIG. 6). If there is only one RSSI value (NO in step S4 in FIG. 6), the portable machine 20 receives the response request signal from only one of the LF transmitters 2 to 6. The communication can thus be determined as relay attack. In this case, the controller 1 inhibits door locking/unlocking (step S9 in FIG. 6), and also inhibits starting the engine of the vehicle 30 (step S10 in FIG. 6).

In contrast, if there are at least two RSSI values included in the response signal (YES in step S4 in FIG. 6), the portable machine 20 receives the response request signals from at least two of the LF transmitters 2 to 6. The communication can be determined as being highly possibly proper communication with the portable machine 20 (e.g. entry by the portable machine 20). The controller 1 determines the position of the portable machine 20 in accordance with the RSSI information in this case (step S5 in FIG. 6).

If the controller 1 determines that the portable machine 20 is located adjacent to the vehicle 30 outside the vehicle chamber (YES in step S6 in FIG. 6), the controller 1 collates the ID code of the portable machine 20 included in the response signal with the ID code preliminarily stored in the internal memory. If matching of the ID codes is unsuccessful (NO in step S7 in FIG. 6), the controller 1 inhibits door locking/unlocking (step S9 in FIG. 6), and also inhibits starting the engine of the vehicle 30 (step S10 in FIG. 6).

In contrast, if matching of the ID codes is successful (YES in step S7 in FIG. 6), the controller 1 permits door locking/unlocking (step S8 in FIG. 6). The door lock device 15 accordingly unlocks the doors of the vehicle 30 so as to allow a user carrying the portable machine 20 to enter the vehicle chamber.

If the user subsequently enters the vehicle 30 and the portable machine 20 is placed in the vehicle chamber as depicted in FIG. 5A, at least two of the transmission antennas 2a to 6a of the LF transmitters 2 to 6 enter the signal receivable area E1 of the portable machine 20. As described above, the LF receiver 22 in the portable machine 20 thus receives, within the predetermined time period T1, at least two of the response request signals transmitted from the LF transmitters 2 to 6 in step S1 in FIG. 6 (step S21 in FIG. 7). Furthermore, the RSSI detector 22b detects the RSSI value of each of the response request signals (step S22 in FIG. 7). After the predetermined time period T1 elapses (YES in step S23 in FIG. 7), the controller 21 generates a response signal including the RSSI information and the ID code (step S24 in FIG. 7) and the UHF transmitter 23 transmits the response signal to the vehicle control device 10 (step S25 in FIG. 7).

The UHF receiver 7 in the vehicle control device 10 receives the response signal from the portable machine 20 as described above (YES in step S2 in FIG. 6), and the controller 1 checks that the response signal includes at least two RSSI values (YES in step S4 in FIG. 6) and determines the position of the portable machine 20 (step S5 in FIG. 6). If the controller 1 determines that the portable machine 20 is located not adjacent to the vehicle 30 outside the vehicle chamber (NO in step S6 in FIG. 6) but in the vehicle chamber (YES in step S11 in FIG. 6), the controller 1 collates the ID code of the portable machine 20 included in the response signal with the ID code preliminarily stored in the internal memory. If matching of the ID codes is unsuc-

11

cessful (NO in step S12 in FIG. 6), the controller 1 inhibits engine start (step S10 in FIG. 6).

In contrast, if the engine switch 14 is turned ON and matching of the ID codes is successful (YES in step S12 in FIG. 6), the controller 1 permits engine start (step S13 in FIG. 6). The engine device 16 accordingly starts the engine of the vehicle 30 so that the vehicle 30 is ready to be driven.

If the position of the portable machine 20 determined in step S5 in FIG. 6 is neither adjacent to the vehicle 30 outside the vehicle chamber (NO in step S6 in FIG. 6) nor inside the vehicle chamber (NO in step S11 in FIG. 6), the controller 1 inhibits door locking/unlocking (step S9 in FIG. 6), and also inhibits starting the engine of the vehicle 30 (step S10 in FIG. 6).

When the repeater 50 is somehow improperly placed in the vehicle chamber as depicted in FIG. 5B, one of the transmission antennas 2a to 6a of the LF transmitters 2 to 6 enters the signal receivable area E2 of the repeater 50. As described above, the LF receiver 22 in the portable machine 20 thus receives, within the predetermined time period T1, one of the response request signals transmitted from the LF transmitters 2 to 6 in step S1 in FIG. 6 (step S21 in FIG. 7). In this case, after the predetermined time period T1 elapses (YES in step S23 in FIG. 7), the controller 21 generates a response signal including RSSI information indicative of one RSSI value and the ID code (step S24 in FIG. 7) and the UHF transmitter 23 transmits the response signal to the vehicle control device 10 (step S25 in FIG. 7).

Even when the UHF receiver 7 in the vehicle control device 10 receives the response signal from the portable machine 20 as described above (YES in step S2 in FIG. 6), the controller 1 checks that the response signal includes only one RSSI value (NO in step S4 in FIG. 6). The controller 1 thus inhibits door locking/unlocking (step S9 in FIG. 6), and also inhibits starting the engine of the vehicle 30 (step S10 in FIG. 6).

After the processing in step S8, S10, or S13 in FIG. 6 is executed, a reception record and the content of the response signal as well as measurement information on the predetermined time period T2 are cleared in the vehicle control device 10.

According to the first embodiment, when the portable machine 20 approaches the vehicle 30, the LF receiver 22 in the portable machine 20 receives, within the predetermined time period T1, response request signals transmitted from at least two of the LF transmitters 2 to 6 provided to the vehicle 30. The vehicle control device 10 and the portable machine 20 properly communicate with each other in this case. Control to the vehicle 30 by the vehicle control device 10 can thus be permitted.

In contrast, when the portable machine 20 is located far away and the repeater 50 having reception sensitivity much lower than that of the portable machine 20 approaches the vehicle 30, the LF receiver 22 in the portable machine 20 receives, within the predetermined time period T1 via the repeater 50, a response request signal transmitted from one of the LF transmitters 2 to 6. Relay attack is committed using the repeater 50 in this case. Control to the vehicle 30 by the vehicle control device 10 can thus be inhibited.

In summary, control to the vehicle 30 can be permitted or inhibited depending on whether the portable machine 20 receives, within the predetermined time period T1, only one or a plurality of response request signals from the LF transmitters 2 to 6 in the vehicle control device 10, in consideration of the difference in size between the signal receivable areas E1 and E2 of the portable machine 20 and the repeater 50. It is thus possible to improve security

12

against relay attack using the repeater 50 without complication of the processing performed by the vehicle control device 10 and the portable machine 20.

In the portable machine 20 according to the first embodiment, the RSSI detector 22b detects RSSI values of all the response request signals received by the LF receiver 22 within the predetermined time period T1, and the UHF transmitter 23 transmits a response signal including the RSSI values. The vehicle control device 10 permits or inhibits control to the vehicle 30 in accordance with the number of RSSI values included in the response signal that has been transmitted from the portable machine 20 and has been received by the UHF receiver 7. Accordingly, the portable machine 20 has only to reply the response signal including the RSSI values of the received response request signals from the LF transmitters 2 to 6, and the vehicle control device 10 has only to check the number of RSSI values included in the received response signal. It is thus possible to further simplify the processing performed by the vehicle control device 10 and the portable machine 20.

Furthermore, door locking/unlocking or engine start of the vehicle 30 is permitted in the first embodiment if the portable machine 20 receives response request signals transmitted from at least two of the LF transmitters 2 to 6 within the predetermined time period T1. Moreover, door locking/unlocking or engine start of the vehicle 30 is inhibited if the LF receiver 22 in the portable machine 20 receives a response request signal from only one of the LF transmitters 2 to 6 within the predetermined time period T1 via the repeater 50. The doors are not unlocked and the engine is not started even when a malicious third party commits relay attack using the repeater 50. It is thus possible to prevent crimes such as unauthorized entry to the vehicle chamber and a theft of the vehicle 30.

The vehicle control device 10 and the portable machine 20 according to the second embodiment will be described next in terms of their behavior with reference to FIGS. 8 and 9.

FIG. 8 is a flowchart of behavior of the vehicle control device 10 according to the second embodiment. FIG. 9 is a flowchart of behavior of the portable machine 20 according to the second embodiment.

According to the second embodiment, if the LF receiver 22 in the portable machine 20 receives a response request signal from one of the LF transmitters 2 to 6 in the vehicle control device 10 (YES in step S21 in FIG. 9), the RSSI detector 22b detects an RSSI value of the response request signal thus received (step S22 in FIG. 9). The controller 21 associates the RSSI value of the response request signal detected by the RSSI detector 22b with identification information on the corresponding one of the LF transmitters 2 to 6 that are the originators of the response request signal, and stores the same as RSSI information in an internal memory as needed.

If the predetermined time period T1 elapses after initial receipt of the response request signal from any of the LF transmitters 2 to 6 (YES in step S23 in FIG. 9), the controller 21 refers to the internal memory to check the number of RSSI values of the response request signals.

If the internal memory stores at least two RSSI values (YES in step S23a in FIG. 9), the controller 21 generates a response signal including RSSI information indicative of the RSSI values of all the response request signals and the ID codes (step S24 in FIG. 9). The controller 21 subsequently causes the UHF transmitter 23 to transmit the response signal thus generated to the vehicle control device 10 (step S25 in FIG. 9).

13

In contrast, if the internal memory stores only one RSSI value (NO in step S23a in FIG. 9), the controller 21 causes the UHF transmitter 23 to transmit, to the vehicle control device 10, an inhibiting signal indicative of inhibition of door locking/unlocking and engine start (step S26 in FIG. 9).

Assume that, after the LF transmitters 2 to 6 transmit response request signals (step S1 in FIG. 8) and before the predetermined time period T2 elapses (NO in step S3 in FIG. 8), the UHF receiver 7 in the vehicle control device 10 receives not a response signal but an inhibiting signal from the portable machine 20 (YES in step S2a in FIG. 8). In this case, the controller 1 inhibits, in accordance with the inhibiting signal, door locking/unlocking (step S9 in FIG. 8), and also inhibits starting the engine of the vehicle 30 (step S10 in FIG. 8).

In contrast, assume that, after the LF transmitters 2 to 6 transmit response request signals (step S1 in FIG. 8) and before the predetermined time period T2 elapses (NO in step S3 in FIG. 8), the UHF receiver 7 in the vehicle control device 10 receives a response signal from the portable machine 20 (YES in step S2 in FIG. 8). The controller 1 determines the position of the portable machine 20 in accordance with RSSI information included in the response signal in this case (step S5 in FIG. 8). If the controller 1 determines that the portable machine 20 is located adjacent to the vehicle 30 outside the vehicle chamber (YES in step S6 in FIG. 8) and then matching of the ID codes is successful (YES in step S7 in FIG. 8), the controller 1 permits door locking/unlocking (step S8 in FIG. 8).

If the controller 1 determines that the portable machine 20 is located inside the vehicle chamber after the engine switch 14 is turned ON (YES in step S11 in FIG. 8) and matching of the ID codes is successful (YES in step S12 in FIG. 8), the controller 1 permits engine start (step S13 in FIG. 8).

According to the second embodiment, if the portable machine 20 receives response request signals transmitted from at least two of the LF transmitters 2 to 6 within the predetermined time period T1, the portable machine 20 transmits, to the vehicle control device 10, RSSI values of the response request signals along with a response signal. When the vehicle control device 10 receives the response signal, permitted in accordance with the response signal are door locking/unlocking and engine start of the vehicle 30. In other words, control to the vehicle 30 can be permitted if the vehicle control device 10 and the portable machine 20 properly communicate with each other.

If the portable machine 20 receives a response request signal transmitted from one of the LF transmitters 2 to 6 within the predetermined time period T1, the portable machine 20 transmits an inhibiting signal to the vehicle control device 10. When the vehicle control device 10 receives the inhibiting signal, door locking/unlocking and engine start of the vehicle 30 are inhibited. In other words, control to the vehicle 30 can be inhibited when relay attack is committed using the repeater 50.

It is thus possible to improve security against relay attack using the repeater 50 without complication of the processing performed by the vehicle control device 10 and the portable machine 20.

According to the second embodiment, if the portable machine 20 receives a response request signal from one of the LF transmitters 2 to 6 within the predetermined time period T1, the portable machine 20 transmits, to the vehicle control device 10, an inhibiting signal including no RSSI value. When the vehicle control device 10 receives the inhibiting signal, the vehicle control device 10 inhibits door locking/unlocking and engine start with no other processing.

14

This further simplifies the processing performed by the vehicle control device 10 and the portable machine 20.

The disclosure can be achieved in various embodiments in addition to those described above. An illustrative embodiment exemplifies the case where the vehicle control device 10 determines the position of the portable machine 20 in accordance with RSSI information included in a response signal received from the portable machine 20. The disclosure is, however, not limited to this case. For example, the processing performed by the vehicle control device in step S5, S6, or S11 in FIG. 6 or 8 relevant to the position of the portable machine may not be performed.

An illustrative embodiment exemplifies door locking/unlocking and engine start as control to the vehicle permitted or inhibited in the vehicle wireless communication system 100. The disclosure is, however, not limited to this case. Alternatively, either door locking/unlocking or engine start of the vehicle can be permitted or inhibited. Still alternatively, control other than the above to the vehicle can be permitted or inhibited.

An illustrative embodiment exemplifies the case where the two LF transmitters 2 and 3 are provided inside the chamber of the vehicle 30 whereas the three LF transmitters 4 to 6 are provided outside the chamber. The disclosure is, however, not limited to this case. Otherwise, one or at least three first transmitters can be provided inside the vehicle chamber whereas one, two, or at least four first transmitters can be provided outside the vehicle chamber, and each of the first transmitters can transmit a response request signal. That is, the plurality of first transmitters only needs to be provided inside and outside the vehicle chamber such that response request signals reach an area around the vehicle and the interior of the vehicle chamber.

An illustrative embodiment exemplifies the case where the disclosure is applied to the vehicle wireless communication system 100, the vehicle control device 10, and the portable machine 20 for an automatic four-wheeled vehicle. The disclosure is also applicable to a vehicle wireless communication system, a vehicle control device, and a portable machine for a vehicle of a different type such as a motorcycle or a large motor vehicle.

While the invention has been described with reference to a limited number of embodiments, those skilled in the art, having benefit of this disclosure, will appreciate that other embodiments can be devised which do not depart from the scope of the invention as disclosed herein. Accordingly, the scope of the invention should be limited only by the attached claims.

The invention claimed is:

1. A vehicle wireless communication system configured to cause a vehicle control device mounted on a vehicle to control the vehicle in accordance with a wireless signal transmitted and received between the vehicle control device and a portable machine carried by a user,

the vehicle control device comprising:

a first transmitter configured to transmit a response request signal to the portable machine;
a first receiver configured to receive a response signal from the portable machine; and
a first controller that controls the first transmitter and the first receiver;

the portable machine comprising:

a second receiver configured to receive the response request signal from the vehicle control device; and

15

a second transmitter configured to transmit the response signal to the vehicle control device in reply to the response request signal received by the second receiver;

wherein the first transmitter comprises a plurality of first transmitters to allow the response request signals to reach an area around the vehicle and an interior of a vehicle chamber,

wherein the second receiver comprises a reception region in which the response request signals transmitted from at least two of the first transmitters are receivable by the second receiver when the portable machine approaches the vehicle,

wherein control to the vehicle is permitted if the second receiver receives the response request signals transmitted from at least two of the first transmitters within a predetermined time period,

wherein control to the vehicle is inhibited if the second receiver receives the response request signal transmitted from one of the first transmitters within the predetermined time period,

wherein the portable machine causes the second transmitter to transmit the response signal comprising reception information according to the number of response request signals received by the second receiver within the predetermined time period,

wherein the vehicle control device permits or inhibits control to the vehicle in accordance with the reception information comprised in the response signal after the first receiver receives the response signal transmitted from the portable machine, and

wherein the first controller in the vehicle control device permits control to the vehicle if the reception information included in the response signal indicates that the portable machine receives the response request signals transmitted from at least two of the first transmitters, and inhibits control to the vehicle if the reception information indicates that the portable machine receives the response request signal transmitted from one of the first transmitters.

2. A vehicle wireless communication system configured to cause a vehicle control device mounted on a vehicle to control the vehicle in accordance with a wireless signal transmitted and received between the vehicle control device and a portable machine carried by a user,

the vehicle control device comprising:

a first transmitter configured to transmit a response request signal to the portable machine; and
a first receiver configured to receive a response signal from the portable machine;

the portable machine comprising:

a second receiver configured to receive the response request signal from the vehicle control device; and
a second transmitter configured to transmit the response signal to the vehicle control device in reply to the response request signal received by the second receiver;

wherein the first transmitter comprises a plurality of first transmitters to allow the response request signals to reach an area around the vehicle and an interior of a vehicle chamber,

wherein the second receiver comprises a reception region in which the response request signals transmitted from at least two of the first transmitters are receivable by the second receiver when the portable machine approaches the vehicle,

16

wherein control to the vehicle is permitted if the second receiver receives the response request signals transmitted from at least two of the first transmitters within a predetermined time period,

wherein control to the vehicle is inhibited if the second receiver receives the response request signal transmitted from one of the first transmitters within the predetermined time period,

wherein in the portable machine,

if the second receiver receives the response request signals transmitted from at least two of the first transmitters within the predetermined time period, the second transmitter transmits the response signal comprising reception information according to the number of response request signals,

if the second receiver receives the response request signal transmitted from one of the first transmitters within the predetermined time period, the second transmitter transmits an inhibiting signal indicative of inhibition of control to the vehicle, and

wherein the vehicle control device permits control to the vehicle in accordance with the response signal if the first receiver receives the response signal transmitted from the portable machine, and

inhibits control to the vehicle if the first receiver receives the inhibiting signal transmitted from the portable machine.

3. The vehicle wireless communication system according to claim 1,

wherein the portable machine further comprises a reception strength detector configured to detect reception strength of the response request signal received by the second receiver, and

wherein the reception information relates to reception strength values detected by the reception strength detector, of all the response request signals received by the second receiver within the predetermined time period.

4. A vehicle control device mounted on a vehicle and configured to control the vehicle in accordance with a wireless signal transmitted and received to and from a portable machine carried by a user, the vehicle control device comprising:

a first transmitter configured to transmit a response request signal to the portable machine comprising a reception region in which signals from a plurality of transmitters are receivable when the portable machine approaches the vehicle;

a first receiver configured to receive a response signal transmitted from the portable machine in reply to the response request signal; and

a first controller configured to control the first transmitter and the first receiver;

the portable machine comprising:

a second receiver configured to receive the response request signal from the vehicle control device; and
a second transmitter configured to transmit the response signal to the vehicle control device in reply to the response request signal received by the second receiver;

wherein the first transmitter comprises a plurality of first transmitters to allow the response request signals to reach an area around the vehicle and an interior of a vehicle chamber, and

17

wherein after the first receiver receives the response signal transmitted from the portable machine, the first controller permits control to the vehicle if reception information according to the number of response request signals received by the portable machine within a predetermined time period indicates that the portable machine receives the response request signals transmitted from at least two of the first transmitters, the reception information comprised in the response signal, and

10 inhibits control to the vehicle if the reception information comprised in the response signal indicates that the portable machine receives the response request signal transmitted from one of the first transmitters, wherein the first controller in the vehicle control device permits control to the vehicle if the reception information included in the response signal indicates that the portable machine receives the response request signals transmitted from at least two of the first transmitters, and inhibits control to the vehicle if the reception information indicates that the portable machine receives the response request signal transmitted from one of the first transmitters.

15 5. A vehicle control device mounted on a vehicle and configured to control the vehicle in accordance with a wireless signal transmitted and received to and from a portable machine carried by a user, the vehicle control device comprising:

a first transmitter configured to transmit a response request signal to the portable machine comprising a reception region in which signals from a plurality of transmitters are receivable when the portable machine approaches the vehicle;

a first receiver configured to receive a response signal transmitted from the portable machine in reply to the response request signal; and

20 a first controller configured to control the first transmitter and the first receiver;

wherein the first transmitter comprises a plurality of first transmitters to allow the response request signals to reach an area around the vehicle and an interior of a vehicle chamber,

25 wherein after the first receiver receives the response signal transmitted from the portable machine, the first controller

permits control to the vehicle if reception information according to the number of response request signals received by the portable machine within a predetermined time period indicates that the portable machine receives the response request signals transmitted from at least two of the first transmitters, the reception information comprised in the response signal, and

18

inhibits control to the vehicle if the reception information comprised in the response signal indicates that the portable machine receives the response request signal transmitted from one of the first transmitters, wherein the first controller

receives at the first receiver an inhibiting signal instead of the response signal transmitted from the portable machine if the portable machine receives the response request signal transmitted from one of the first transmitters within the predetermined time period, and inhibits control to the vehicle in accordance with the inhibiting signal.

6. A portable machine configured to transmit and receive a wireless signal for control to a vehicle to and from a vehicle control device comprising a plurality of first transmitters configured to transmit response request signals that reach an area around the vehicle and an interior of a vehicle chamber, the portable machine comprising:

a second receiver configured to receive the response request signal transmitted from the vehicle control device;

a second transmitter configured to transmit a response signal to the vehicle control device in reply to the response request signal received by the second receiver; and

a second controller configured to control the second transmitter and the second receiver;

wherein the second receiver comprises a reception region in which the response request signals transmitted from at least two of the first transmitters are receivable when the portable machine approaches the vehicle,

wherein the second controller causes the second transmitter to transmit, to the vehicle control device, the response signal comprising reception information according to the number of response request signals received by the second receiver within a predetermined time period,

wherein the reception information indicating receipt of the response request signals transmitted from at least two of the first transmitters is for permission of control to the vehicle by the vehicle control device, and

wherein the reception information indicating receipt of the response request signal transmitted from one of the first transmitters is for inhibition of control to the vehicle by the vehicle control device.

7. The portable machine according to claim 6, wherein the second controller causes the second transmitter to transmit an inhibiting signal indicative of inhibition of control to the vehicle instead of the response signal if the second receiver receives the response request signal transmitted from one of the first transmitters within the predetermined time period.
